JOHN F. MITCHELL, OF SANTA MONICA, CALIFORNIA, ASSIGNOR TO ETHEL P. YOUNG,
OF LOS ANGELES, CALIFORNIA.

LAMP.

1,141,880.

Specification of Letters Patent.

Patented June 1, 1915.

Application filed December 29, 1914. Serial No. 879,469.

To all whom it may concern:

Be it known that I, JOHN F. MITCHELL, a citizen of the United States, residing at Santa Monica, in the county of Los Angeles and State of California, have invented new and useful Improvements in Lamps, of which the following is a specification.

This invention relates to lamps and more particularly to lamps in connection with which reflectors or other projecting means are employed for throwing the light or concentrating the light, for various purposes of illumination or image display.

The invention further concerns lamps in connection with which hoods, shields or like devices are employed for protecting the lamp, preventing blurring up or interference with the rays or images projected thereby, and further confining the projection of the light rays to certain paths or zones.

More specifically the invention relates to lamps employed for illuminating the paths of moving vehicles, vessels and the like, in which it is highly important that the light rays concentrate upon such path, and that the projection of such light rays be confined to a definite zone of projection so as to prevent the diffused glare and blinding effect otherwise produced, and which, in the case of automobile and other vehicle lamps, is confusing and disturbing to pedestrians, draft animals and the drivers of other vehicles. It is likewise important in connection with this class of lamps that accumulations of rain, fog and other moisture upon the projecting and other lamp surfaces be prevented.

In practising the invention, I provide an improved lamp in which the several desiderata are taken into consideration; with the result that a better and more properly controlled and concentrated light projection is caused, and in which the projecting and protecting surfaces of the lamp are sufficiently guarded against deposition of moisture and other dimming and interfering substances.

The invention is particularly adapted for use in connection with speedy vehicles and vessels, such as automobiles, high-powered boats, and aerial craft.

With the above and other objects in view, including relative simplicity and inexpensiveness in construction, length of life or durability and general efficiency, the invention consists in the novel and useful provision, construction, formation, combination, association and inter-relation of parts, members and features, all as hereinafter described, shown in the drawing and finally pointed out in claim.

In the drawing: Figure 1 is a front elevation of an automobile lamp, in detached position, and organized to embody the invention; Fig. 2 is a side elevation of the same; Fig. 3 is a vertical sectional view of the same, taken on the line x^3-x^3 , Fig. 1, and looking in the direction of the appended arrows; and Fig. 4 is a detail view, on a reduced scale, of a holding device whereby several of the parts shown in the other figures are maintained in assemblage, such holding device likewise being indicated in Fig. 3.

Corresponding parts in all the figures are designated by the same reference characters.

Referring with particularity to the drawing, the improved lamp shown therein as embodying the invention comprises a body A within which is housed or hooded a source of illumination a, which, in the present instance, is shown as comprising an incandescent electric lamp, the same projecting through and substantially centrally of a reflector 5 which is in part housed within the body A, which latter comprises a substantially semi-spherical shield 6 forming the chamber within which the incandescent lamp a and the major portion of the reflector 5 are housed; said lamp being supplied with energy through circuit wires 7 led into the housing or shield 6 through a nipple 8 thereon. The reflector 5, together with the transparent or glass cover or plate 9 applied to the forward or outer portion of the reflector, and the incandescent lamp a carried by the reflector, further in connection with an auxiliary reflector and shield 10 are directly carried by or mounted upon a swinging member B hinged to the body member A at one side, as at 11, fastening means b being provided for holding the free edge or side

of said member B to the body member A. Thus, access may be had to the various features of the lamp, and such features may readily be assembled and taken apart. The 5 swinging member B preferably comprises an annulus 12 provided with a peripheral outer lip 12^a rearward of which is disposed the glass or transparent plate 9, the supplemental reflector or shield 10 being held at 10 one edge between such lip and glass plate; and the reflector 5 fits at its periphery against the marginal portion of the glass plate 9, at the rearward surface thereof, the forward surface of such glass plate abutting 15 against the supplemental reflector and shield 10 as last stated.

c designates holding means whereby the reflector 5, the auxiliary reflector 10, and the glass plate 9 are held together and in 20 assemblage with the annulus 12 of the swinging member B; such means c preferably or suitably consisting of a split ring 13 which is applied to a peripheral lip 5^a upon the reflector 5, and which, when the parts 25 carried by the swinging member B are in assemblage as above recited, is disposed in a groove, channel or seat 14 formed in the inner wall of the annulus 12, to maintain the parts in such assemblage; said split ring 30 13 having bent end portions or fingers 13^a which may readily be engaged, when the swinging member B is opened, to enable such split ring to be removed from its seat 14, whereupon the reflector 5 and glass plate 35 9 and auxiliary reflector or shield 10 may be released from assemblage for purposes of cleaning, repairing, lamp substitution and the like. The fastening means b may comprise a pronged plate 15 attached at one end 40 to the shield 6 and receiving between its furcations or prongs the threaded stem of a threaded thumb piece 16 carried by the annulus 12. The auxiliary reflector and shield 10 is preferably curved transversely of the 45 swinging member B, and projects forwardly therefrom and downwardly into the light-projecting area of the lamp approximately to the central zone thereof; and is provided with a marginal lip 10^a which readily seats 50 beneath the lip 12^a upon the annulus 12.

The operation, method of use and advantages of the improvements in lamps constituting the invention will be readily understood from the foregoing description, taken 55 in connection with the accompanying drawing and the following statement: The auxiliary reflector and shield 10 is readily applied to the remaining features of the lamp, as by the lip 10^a thereon which co-operates 60 with the lip 12^a on the annulus 12; and is thus, or by other suitable means, readily attachable to lamps of usual and standard construction, whereby the same may be transformed into the complete lamp device embodying the invention. The auxiliary re-

flector and shield 10, the inner surface of which will be understood is bright and reflecting and the outer surface of which may be finished or decorated as desired, co-operates with the reflector 5, which may be parabolic or of other geometric or preferred form or conformation with a bright forward surface. Such co-operation tends to highly concentrate the light rays emanating from the lamp proper a, and to increase the outward 75 and forward projection of the same, as well as to extend the downward reflection of the same for the purpose of highly illuminating a more immediate field directly in front of the lamp, as for instance, the main immediate 80 path or road to be taken by a vehicle carrying such lamp. Such auxiliary shield likewise serves to prevent the scattering projection and radiation of light rays which otherwise would occur, interfering with the 85 vision of men and animals in the path thereof, as upon a roadway, and tending to produce confusion and discomfort. Such auxiliary reflector or shield 10 likewise serves as a hood and protector for the lamp 90 device, saving the same from injury due to contact with missiles such as flying gravel and pebbles, birds, and other objects the impact of which upon the lamp and the glass front plate thereof would tend to break or 95 damage the same; and said shield 10 tends likewise to keep the glass front plate 9 free from accumulations of fog, rain and other moisture, as well as dust and other substances which would otherwise dim the rays 100 projected from the lamp and decrease its efficiency.

The entire lamp device is highly superior in point of efficiency and serviceability, because of the features provided and mode of 105 operation above pointed out, and serves effectively to cast a concentrated illumination, without the confusing and annoying glare of dissipation of light rays by overhead radiation, and the reflecting and protecting surfaces, which are of particular advantage in vehicle practice, are secured against damage by flying missiles and objects and the dimming accumulations of fog and other moisture and dust or mud.

It is manifest that many changes may be made in the details of construction, formation, combination and assemblage of parts, members and features embodying the invention, all without departing from the 110 spirit of the invention and the terms of the following claim.

Having thus disclosed my invention, I claim and desire to secure by Letters Patent:

A lamp having a body within which are disposed a source of illumination and a main reflector, a swinging member hinged upon said body, and a supplemental reflector carried by the swinging member; said 125 130 135

swinging member comprising an annulus provided with a flange, said supplemental reflector being provided with a flange adapted to be engaged with said flange in said annulus, there being a transparent plate applied to the flange of said supplemental reflector and means being provided for co-operation with the annulus to hold the transparent plate to the flange upon the supplemental reflector and said flange to the 10 flange upon the annulus.

In testimony whereof, I have signed my name to this specification in the presence of two subscribing witnesses.

JOHN F. MITCHELL.
